UNITED STATES PATENT OFFICE.

ALBERT COLLET, OF PARIS, FRANCE, ASSIGNOR TO SOCIETE MAURICE ET PIERRE COLLET & CIE., OF PARIS, FRANCE.

GENERATING SET MOBILE UPON RAILS.

1,387,431.

Specification of Letters Patent. Patented Aug. 9, 1921.

Application filed April 28, 1915. Serial No. 24,617.

(GRANTED UNDER THE PROVISIONS OF THE ACT OF MARCH 3, 1921, 41 STAT. L., 1313.)

To all whom it may concern:

Be it known that I, ALBERT COLLET, a citizen of the Republic of France, residing in Paris, France, have invented certain new and useful Improvements in Generating Sets Movable Upon Rails, (for which I have filed applications in France, April 30, 1914, No. 471,735, and in Germany May 28, 1914,) of which the following is a full and complete specification.

This invention relates to a generating set movable upon rails, which can be moved by four men when the train arrives and replaced after the train has passed. This generating set is designed to supply the different apparatus used in the installing and upkeep of railway systems without being compelled to resort to a fixed junction wire; it constitutes a powerful and light source of electric energy (for power or light) and easily transportable for use at any point along the railway.

This generating set mainly consists of two relatively light parts each weighing less than 250 kilogs. in working order; the first part comprises the frame of drawn steel tubes mounted upon rollers with ball bearings and the continuous current generator; the second part consists in the oil or petrol explosion engine, its fly wheel, its tank, the radiator, the fan and an electric regulator.

This generating set is arranged so as to be capable of adaptation to different widths of track by the movement of the rollers over the transverse tubes of the frame, and the dynamo is also mounted in such a manner as to allow of it being moved nearer to or farther away from the engine.

The engagement is effected instantaneously by a tightener roller movable to and from the axis of the drive pulley of the generator. A special arrangement of brake allows of stopping the carriage in whatever direction the control handle of the said brake may be actuated. Moreover, the action of the brake is equally distributed over both the blocked wheels.

Figures 1 and 2 represent respectively in side view and end view the generating set forming the subject of this invention.

Figs. 3, 3^a and 4, 4^a are side and top views of the brake drawn to a larger scale.

Fig. 5 is a diagram illustrating in plan the working of the arrangement.

The generating set consists of a metal frame made of four perpendicular tubes forming a rectangle, *a*, *a*, *b*, *b* which frame rests upon rollers *c* mounted upon balls. On each side of the said frame are mounted by means of sleeves, the platforms *d*¹ and *d*².

Upon the platform *d*¹ rests the four stroke petrol motor *e* provided with two bars *m* for holding and carrying it and its accessories, the radiator *f* and the petrol tank *g*. The other platform *d*² is designed to receive a tool chest. In the middle is mounted by means of movable clamping sleeves *i* and bars *j*, the electric generator *k* provided with the hand rail *l* for holding and carrying it.

The driving of the generator is effected by means of a band *n* passing over the fly wheel *h* of the engine and around the pulley of the generator *k*. A roller *p* serves to give the required tension and passage to the band and is mounted upon the generator in such a manner that it can rock around the shaft *q* and thus cause the instantaneous engagement or disengagement of the band.

In order to vary the distance of the shafts of the engine and generator it is only necessary to loosen the nuts of the sleeves *i* and to move the generator along the tubes *b*—*b* of the frame.

One of the portions of the frame of the generating set, that is to say, the tubular frame with the generator can be carried by four men holding the ends of the frame, while the engine and its accessories are carried by lifting them by means of the bars *m* above referred to.

Moreover, a special braking arrangement allows of stopping the carriage by acting upon one pair of wheels upon the same axle or upon the other pair according as the rotation of the driving wheel is effected in one direction or the other.

This result is easily obtained by the following arrangement:—

A shaft *a*¹ actuated by a crank handle *b*¹ at each end can turn and slide in bearings *c*¹. This shaft *a*¹ is provided with two screw-threads of opposite hand *o*¹, *o*² on which two ring nuts *h*¹, *h*² can move. One of these rings *h*¹ for example, by means of a stud or

finger moves a fork f^1 fixed to a lever jointed at g^1 . This lever is connected by a shaft h^1 to the connecting rod l^1 on which are mounted the shoes m^1 and n^1 acting upon two 5 wheels of the same rail. The operation is as follows:—

Supposing the rotation of the shaft a^1 is effected so as to move the nut h^1 upon the shaft a^1 in the direction of the arrow f^2 , 10 Figs. 4 and 5, the other nut operated by a thread of opposite hand will move in the opposite direction. It will be seen, therefore, that the movement transmitted through the medium of the forks and levers will 15 cause the tightening of the shoe m^1 .

If, at this moment the other shoe of the same axle is not yet blocked, the rotation of the shaft a^1 continuing in the same direction, the nut h^1 having become fixed, there 20 will follow a movement of translation from a^1 in this nut in reverse direction of the arrow, the effect of which movement is to increase the displacement of the nut h^2 and therefore to contribute to the locking of the 25 second shoe.

If on the contrary, the shaft a^1 has been rotated in the reverse direction, consequently moving the two nuts h^1 , h^2 away from one another, it will be seen that the tightening 30 will be insured by the shoes of the wheels corresponding to the other axle. The actuation of the brake therefore, requires no reflection since the stopping of the carriage is insured by the rotation of the crank handle 35 in either direction, and the action of the shoes is the same upon the two blocked wheels.

Claims:

1. A mobile electricity generating set for 40 use on rails and adapted for quick removal from the rails, comprising a carriage, a manually removable internal combustion engine unit removably seated on said carriage,

an electric generator on said carriage, and a detachable driving connection between said 45 engine and generator.

2. A mobile electricity generating set for use on rails and adapted for quick removal from the rails, comprising a carriage, a manually removable internal combustion 50 engine unit removably seated on said carriage, an electric generator on said carriage, a belt connecting said engine and generator, and a displaceable roller for tensioning the 55 belt, said roller permitting of the ready loosening and displacement of the belt and consequent quick removal of the engine unit.

3. A mobile electricity generating set for use on rails and adapted for quick removal from the rails, comprising a carriage, an 60 internal combustion engine unit removably seated on said carriage, an electric generator on said carriage, and a driving connection between said engine and generator, said carriage comprising a plurality of parallel bars, 65 said electric generator being adjustably mounted on said bars with relation to the engine unit.

4. A mobile electricity generating set for use on rails and adapted for quick removal from the rails, comprising a carriage, a manually removable internal combustion engine unit 70 removably seated on said carriage, said engine unit having handles adapted to be grasped by workmen at two sides of the unit, 75 an electric generator on said carriage, and a driving connection between said engine and generator.

In witness whereof I have hereunto signed my name in the presence of two subscribing 80 witnesses.

ALBERT COLLET.
